(57) **CLAIM**

The ornamental design for a ambu-bag squeezing device, as shown and described.

DESCRIPTION

FIG. 1 is a top perspective of the ambu-bag squeezing device design of the present invention;

FIG. 2 is a top perspective of the device of FIG. 1 with an ambu-bag shown in phantom lines;

FIG. 3 is a front elevation view thereof;

FIG. 4 is a side elevation view thereof;

FIG. 5 is a side elevation view thereof;

FIG. 6 is a top plan view thereof;

FIG. 7 is a rear elevation view thereof; and,

FIG. 8 is a bottom plan view thereof.

The ambu-bag shown in broken lines in the FIG. 2 represents the environment and forms no part of the claimed design.
